UNITED STATES PATENT OFFICE.

ROBERT H. AHN, OF SAN FRANCISCO, CALIFORNIA.

DESIGN FOR A BRACELET.

SPECIFICATION forming part of Design No. 14,438, dated November 27, 1883.

Application filed June 22, 1883. Term of patent 3½ years.

To all whom it may concern:

Be it known that I, ROBERT H. AHN, a citizen of the United States, residing at San Francisco, in the county of San Francisco, State of California, have invented and produced a new and original Design for Bracelets, of which the following is a specification, reference being had to the accompanying drawings, forming part thereof.

10 My invention relates to a design for bracelets. Figure 1 is a perspective view of my bracelet, and Fig. 2 is a section of the same on the line *x x* of Fig. 1.

Heretofore bracelets have been formed of 15 rounded wires bent into the proper oval or circular shape to inclose the wrist, the ends extending past each other a short distance when in place, and having ornamental end or other devices, the elasticity of the hoops retaining them in place on the arm.

20 My design consists of a hoop or bracelet having its outer periphery concaved, so as to show one or more grooves or channels.

A. is the bracelet, having its outer periphery or back deeply concaved or channelled longitudinally, as at B, and the inner surface convex in cross-section. One or more of these concave-convex pieces may be formed according to the width of the bracelet, and have an ornamental twisted wire within the channel, 25 and any desired exterior ornamental ends or clasps; but these ends or clasps form no part of my design, which consists of the concave-convex hoop, as shown.

Having thus described my invention, what 30 I claim as new is—

The design for bracelets, consisting of the concave-convex hoop or ring A, with the ornamental twisted wire within the channel, as shown and described.

35 In witness whereof I have hereunto set my hand.

ROBERT H. AHN.

Witnesses:

S. H. NOURSE,
G. B. STUDLEY.
